[57] CLAIM

The ornamental design for a retail terminal or similar article, as shown and described.

DESCRIPTION

FIG. 1 is a left, front perspective view of a retail terminal or similar article showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and FIG. 7 is a left, front perspective view thereof. The broken line showing of a keyboard in FIGS. 2-7 is environmental only and forms no part of the claimed design.

FIG. 1

FIG. 2

FIG. 3

FIG. 4

FIG. 5

FIG. 6

FIG. 7
